SQUEEGEE ROLLER ARRANGEMENT

BACKGROUND OF THE INVENTION

This invention relates to roller arrangements for apparatus such as photographic processing apparatus in which excess liquid applied to a sheet, web or film is removed by a pair of rollers in the roller arrangement.

One roller arrangement used in a photographic print processing apparatus comprises a pair of similar rubber covered rollers respectively mounted for rotation about horizontal axes, one roller being disposed vertically above the other, and the lower roller being partly immersed in a bath of processing liquid. During operation the rollers are driven in opposite senses to produce forward movement of a print being passed therebetween, and the lower roller acts as an applicator roller to apply processing liquid to the lower side of the print. Excess liquid squeezed from the print as it enters the nip of the roller forms a liquid bead in front of the nip and may return to the bath. Under some conditions there is a tendency for liquid from the bead to travel around the ends of the lower roller and wet the upper roller. This may cause undesirable rewetting of the print, and it is an object of the present invention to provide a roller arrangement which reduces or obviates this tendency.

SUMMARY OF THE INVENTION

According to the present invention, in a roller arrangement for a photographic processing apparatus or other apparatus in which excess liquid is removed from a sheet, web or film by a pair of rollers in the roller arrangement, the outer surface of the lower one of the pair of rollers is of substantially the same axial length as the cooperating surface of the other roller during operation, and the ends of the said lower roller are formed so that an acute angle is defined at each peripheral edge between its outer surface and the adjacent portion of the end of the roller.

The cooperating surface of the lower roller is preferably slightly longer rather than shorter than the cooperating surface of the upper roller.

The ends of the lower roller may be of dished form to produce the desired sharp peripheral edge.

The rollers may be urged together by pressure which causes deformation of the end faces of the lower roller during operation.

The various features of novelty which characterize the present invention are pointed out with particularity in the claims annexed to and forming a part of this specification. For a better understanding of the invention, its operating advantages and the specific objects obtained by its use, reference should be had to the accompanying drawing and descriptive matter in which a preferred embodiment of the present invention is illustrated and described.

DESCRIPTION OF THE PREFERRED EMBODIMENT

Referring to the drawing, the roller arrangement comprises an upper roller 11 and a lower roller 12, both rollers preferably having a cylindrical outer surface provided by a coating of rubber, 13 and 14, or other deformable material, on a shaft, 15 and 16. The shaft 16 of lower roller 12 is mounted horizontally in bearings in spaced vertically disposed support members 17 so that the outer surface can dip into processing liquid 18 contained in a trough 19. The shaft 15 of upper roller 11 is also carried by movable bearings in the support members

17, and this roller is biased downwardly by springs 20 into contact with the lower roller to form a substantially horizontal nip therebetween.

The upper and lower rollers have cylindrical outer surfaces of similar radius and substantially identical length. When the rollers are pressed together for operation the lower roller may be as long as the upper roller or may be marginally greater in length, say 0.01 inch longer.

The ends 21 of the lower roller 12 are concave so as to produce sharp peripheral edges 22 to the cylindrical outer surface of this roller. For this purpose the ends are concave and may be dished or, as shown, frustoconical in shape. In the latter case successful operation has been obtained with an acute angle at the peripheral edge of from 65° to 70° between the outer surface and each end face. The pressure between the rollers produced by the springs 20 is preferably sufficient to deform the lower roller 12 to form a lip 23 at its ends and reduce the acute angle at the peripheral edge between the rollers. This deformation of the end faces of the lower roller tends to deflect away from the upper roller any liquid which is carried upwardly by the end faces of the lower roller.

In operation of the processing apparatus a sheet of photographic paper is passed between the rollers 11 and 12. The rollers rotate in opposite senses with the sheet, and the lower roller applies liquid from the trough to the underside of the sheet. Excess liquid is removed by the rollers. Effective operation of the roller arrangement has been obtained in practice with a decreased tendency for wetting of the top surface of the sheet.

Although the invention has been described in relation to a roller arrangement having a lower roller which constitutes a liquid applicator it should be appreciated that the invention is also applicable to arrangements where liquid is only removed from the sheet, web or film.

Thus, it will be seen that the present invention provides a novel roller construction utilizing concave end surfaces whereby the upper roller is not wet by liquids being transferred thereto by the end of the lower roller. As a result, the possibility that a sheet or web being transported by the rollers will have the upper surface wetted is reduced or eliminated.

The invention has been described in detail with particular reference to preferred embodiments thereof, but it will be understood that variations and modifications can be effected within the spirit and scope of the invention.

We claim:

1. In a roller arrangement comprising a pair of substantially horizontally disposed rollers, said rollers being longitudinally and axially aligned with one roller above the other forming a substantially horizontal nip therebetween, the lower roller being at least partially immersed in a liquid and having a resilient peripheral surface, the ends of said lower roller having a concave configuration which is symmetrical about the roller axis and which forms an acute angle between the peripheral surface and each end surface whereby liquid is not transferred around the ends of the lower roller to wet the upper roller.

2. The invention according to claim 1 wherein the length of the lower roller is at least equal to the length of the upper roller.

3. The invention according to claim 1 wherein the upper and the lower rollers are urged together by a radial force whereby the end surfaces of the lower roller are deformed.

4. The invention according to claim 1 wherein the acute angle is between 65° and 70°.
